(57) **CLAIM**

The ornamental design for a portafilter, as shown and described.

DESCRIPTION

FIG. 1 is a front, left and bottom perspective view of a portafilter, showing my design.

FIG. 2 is a rear, right and top perspective view thereof.

FIG. 3 is a front elevation view thereof.

FIG. 4 is a rear elevation view thereof.

FIG. 5 is a left side view thereof.

FIG. 6 is a right side view thereof.

FIG. 7 is a top plan view thereof.

FIG. 8 is a bottom plan view thereof.

FIG. 9 is a partial enlarged view of an area labeled 9 in FIG. 1.

FIG. 10 is a partial enlarged view of an area labeled 10 in FIG. 2.

FIG. 11 is a partial enlarged view of an area labeled 11 in FIG. 3; and,

FIG. 12 is a partial enlarged view of an area labeled 12 in FIG. 4.

The broken lines in the drawings depict portions of the portafilter that form no part of the claimed design. The dot-dash broken lines in the drawings are for the purpose of illustrating the enlarged view indicators and form no part of the claimed design.

1 Claim, 12 Drawing Sheets
